UNITED STATES PATENT OFFICE.

PAUL W. KREUZKAMP, OF BROOKLYN, NEW YORK, ASSIGNOR TO ENGLANDER SPRING BED COMPANY, OF BROOKLYN, NEW YORK.

BED-SPRING.

1,297,698.

Specification of Letters Patent. Patented Mar. 18, 1919.

Application filed October 31, 1914. Serial No. 869,516.

To all whom it may concern:

Be it known that I, PAUL W. KREUZKAMP, a citizen of the United States, residing at Brooklyn, in the county of Kings and State 5 of New York, have invented certain new and useful Improvements in Bed-Springs, of which the following is a specification.

This invention relates to bed springs, more particularly to that form known as 10 spiral bed springs, in which the spring consists of suitable supporting means and spiral springs carried thereby for supporting the ordinary stuffed mattress, the object of the invention being to provide an improved 15 spring of this kind in which certain of the springs may be utilized to partly form a side-guard for preventing the slipping, spreading and flattening of a stuffed mattress.

20 Heretofore it has been found practicable to provide only flat bed springs, that is springs in which the bottom is formed of a fabric of some kind, with side-guards, and although it has been highly desirable to 25 make spiral bed springs with side-guards this has not been found practicable for various reasons, among others the difficulty of attaching and the difficulty of maintaining such side-guards in shape and position, 30 and therefore I believe that I am the first to provide a side guard spiral bed spring in which some of the springs are utilized to form or partly form the side-guards, and by means of which the shifting, spreading 35 and flattening of a stuffed mattress are prevented and such mattress maintained in its box-like shape, and therefore the object of the present improvement is the provision of a bed spring of the class described having side-guards which are inexpensively, 40 but practically, applied and formed in part of the spiral springs themselves, and which structure is durable and practicable, so that the advantages of the ordinary side-guard 45 spring are obtained in the spiral form of bed spring.

In the drawings accompanying and forming part of this specification, Figure 1 is a perspective view of this improved spring; 50 Fig. 2 is an enlarged detail view of a part thereof; and Fig. 3 is a side view of the spring shown in Fig. 1.

Similar characters of reference indicate corresponding parts throughout the several 55 figures of the drawings.

The spiral spring supporting means may consist of any suitable framework 2. In the form shown it consists of a pair of longitudinal extending bars 3 shown as of angle iron form connected crosswise at their ends 60 by suitable angle iron bars 4 and by a series of intermediate bars. Supported by these bars are a series of spiral springs 5 of any suitable form. The angle iron bars 4 are bent upward at their ends as at 8 so as 65 to extend above the spiral springs a predetermined distance, thus forming guard supporting means or brackets 8', and these brackets are connected by braces 9 with the spring supporting means, and the upturned portions of such brackets may also 70 be suitably braced. In the present instance the lower ends of the braces 9 at each side of the bed spring are connected with the outer longitudinal extending bar. The 75 outer row of springs at each side of the bed spring is shown connected by a longitudinally extending wire or rod 6 inturned at its ends 7 and connected along the inner 80 sides of certain of the springs. In the present form of side-guard each spiral spring has its ends so bent upon itself as to form an upright member or projection 10 and one or more loops or eyes 11 at each side thereof. The end of the spiral spring may be 85 utilized to form various styles of uprights or projections, but in the present instance the end of the spiral spring is bent upon itself to form a loop 12, and then again bent upon itself above said loop to form another 90 loop 13, and then bent downward and upon itself to form another loop 14 at the side of the upper loop, and then again bent upon itself to form another loop 15 at the side of the first loop, and the wires then extend 95 downward and are bent around one of the coils of the spiral spring as at 16.

As each of the spiral springs terminates in an upstanding member or projection, it follows that a series thereof are located 100 along each outer edge of the bed spring. Connected with the loops of the upstanding members or projections is a series of wires 17 extending in parallelism with the connecting rod 6 hereinbefore referred to. The 105 end projections are in turn shown connected by spiral springs 18 with the guard supporting brackets hereinbefore referred to.

Of course, it will be understood that as many loops may be formed in each upstand- 110

ing bracket as may be found desirable in practice, and according to the number of connecting wires which it may be desired to locate in parallelism.

5 From the foregoing, it will thus be seen that at each side of the bed spring there is provided a side-guard stretched between the supporting brackets therefor, the members of which side-guard are connected with or 10 formed as a part of the spiral springs upon which the stuffed mattress rests, so that each guard is not only connected at its ends with the brackets preferably through the medium of coil springs thereby to impart 15 a tension to the side-guard, but each guard is also connected, and this in the present instance integrally with the spiral springs themselves, so that the guard tends to resist any compressive force applied to the spiral 20 springs while the compression of the spiral springs causes the guard to move with them so that such guard is always in position to maintain the stuffed mattress in its box-like form and prevent the flattening and spreading 25 thereof, or any shifting that might be present.

By the present construction it will also be observed that the guard projects above the spiral springs the required distance and 30 while the height of the guard may be varied somewhat it is usually about three inches, and therefore extends about this distance above the spiral springs, and it will also be observed that, by reason of the tension 35 imparted to the side-guards through the medium of the coil springs, the side-guard very materially assists in maintaining the outer row of springs in their normal position.

40 By folding the upstanding members in the manner shown it will be seen that each thereof has a certain spring action under pull of the longitudinally extending wires so as to assist in maintaining the guard 45 stretched under tension.

The upstanding projections of the side-guard are tied by suitable wires 19 to the longitudinally extending rod or wire 6.

It will be understood that the various 50 details may be more or less modified without departing from the spirit or scope of the present improvement, for instance, it will be understood that the supporting means as used herein and in the claims may consist of any means which support or connects or ties the several springs into a structure whereby it may be utilized as a spring mattress.

60 The spiral bed springs as frequently called are not infrequently called box springs by reason of the fact that the structure is usually covered with some suitable form of ticking, that is to say, the springs are usually entirely inclosed along the sides, ends and 65 top with ticking, while the bottom is usu-

ally of some cheaper material and, of course, when the spring is so covered the guards could likewise be covered by the ticking also. Of course, it will be understood that the spring structure itself may be so covered without covering the side-guards if this is not desired.

I claim as my invention:

1. A bed spring comprising supporting means, spiral springs carried thereby, and 75 a side-guard located along and supported by each outer longitudinal row of spiral springs to project above the same for preventing a stuffed mattress from flattening, spreading or sagging over the edge of the 80 spring, and consisting of a plurality of upright members located between the ends of the bed spring, and a connecting member or members between said upright members, each of said upstanding members consisting of a part bent upon itself to form 85 one or more eyes at each side thereof.

2. A bed spring comprising supporting means, spiral springs carried thereby, and a side-guard located along each outer longitudinal row of spiral springs to project above the same for preventing a stuffed mattress from flattening, spreading or sagging over the edge of the spring, and consisting of a series of upright members located between the ends of the bed spring, and connecting members between said upright members, each of said upstanding members consisting of a member bent upon 95 itself to form one or more eyes at each side 100 thereof, and each of said upstanding members having connection with a spiral spring.

3. A bed spring comprising supporting means, spiral springs carried thereby, and a side-guard located along each outer longitudinal row of spiral springs to project above the same, each of such side-guards consisting of a plurality of upstanding projections each formed integral with one of 105 said spiral springs and bent to form a plurality of loops, and connecting means between said loops.

4. A bed spring comprising supporting means, spiral springs carried thereby, and a side-guard located along each outer longitudinal row of spiral springs to project above the same, each of such side-guards consisting of a plurality of upstanding projections each formed integral with one of 115 said spiral springs and bent to form a plurality of loops, and connecting means between said loops, each of said projections also having an additional connection with one of the spirals of its spring.

5. A bed spring comprising supporting 125 means, spiral springs carried thereby, and a side-guard located along each outer longitudinal row of spiral springs to project above the same, each of such side-guards consisting of a plurality of upstanding pro-

jections each formed integral with one of said spiral springs and bent to form a plurality of loops, connecting means between said loops, each of said projections also having an additional connection with one of the spirals of its spring, upstanding brackets projecting above said spiral springs

at the corners of the bed spring, and coil springs between said brackets and the end projections.
